UNITED STATES PATENT OFFICE.

RALPH K. REYNOLDS, OF DANBURY, CONNECTICUT.

HAT-POUNCING MACHINE AND THE LIKE.

Application filed June 10, 1926. Serial No. 114,922.

This invention relates to machines used in hat manufacture, such, for example, as hat pouncing machines.

One of the objects of the invention is to provide a machine of the above nature wherein the hats operated upon are presented to the operating tool or tools in an efficient and thoroughly dependable manner. Another object is to provide a machine of the above character having means for supporting a rotating hat in such a manner that uniform action thereon is insured. Another object is to provide means of the above nature adapted to support the hat so that all parts thereof intended to be operated upon are brought into proper engagement with the tool or tools. Another object is to provide apparatus of the above nature which is simple and compact and easily made. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing in which is shown one of the various possible embodiments of this invention,

Figure 1 shows the pouncing pads of a hat brim pouncing machine and a hat supported in operative relation thereto, and

Figure 2 is a top view of Figure 1.

Similar reference characters refer to similar parts in both views of the drawing.

Referring now to the drawing in detail, there is shown diagrammatically a pair of tools 10 and 11 which, in this instance, are pouncing tools and are adapted to operate upon the brims of felt hats. These pouncing tools 10 and 11 are shown mounted upon the outer ends of arms 12 and 13 respectively and their drive is not shown herein since it forms no part of the present invention. Adjacent to the pouncing tools 10 and 11 is shown a hat 14 with the brim 14^a thereof in position between the two pouncing tools or pads to be operated upon thereby. It will be understood that the pads 10 and 11 are rapidly reciprocated in the direction indicated by the double-headed arrow in Figure 2, the two pads preferably moving in opposite directions and pouncing the two sides of the hat brim. The hat is rotatably

supported as will be described presently, and is rotated preferably, in this brim pouncing machine, by means of driven feed rollers 15 which are indicated in Figure 2. The brim 14^a is gripped between a pair of these feed rollers 15 which rotate the hat in the direction indicated by the arrow in Figure 2, drawing the brim 14^a through between the pouncing pads.

The hat 14, while being operated upon, is preferably stretched over and supported upon a hat block 16. The hat block closely fits the interior of the crown of the hat, the hat having been stretched to shape upon this hat block or upon one substantially identical therewith. The feed rollers 15, therefore, gripping the brim of the hat and drawing it through between the pouncing pads, rotate the hat block 16. The hat block shown is of the usual construction, being made of wood and having a central hub 17 in which is a central recess 18. Preferably this recess 18 is provided with a metal bushing 19 to afford better wearing qualities. The hat block and hat are of oval shape and the recess 18 therein is positioned substantially at the center thereof or at the intersection of the major and minor axes of the oval.

The hat block is supported through its hub 17 upon a member 20, the flange 19^a of the bushing 19 resting upon a projecting shoulder 21. The member 20 has a spindle portion 22 which enters the bushing 19 and thus holds the hat block in position and centers the hat block for rotation upon the supporting shoulder 21.

The hat block supporting member 20 is carried in a member 23 which is preferably a substantially upright shaft or rod pivoted at its lower end 24 for swinging movement of its upper end toward and away from the pouncing pads. Suitable means such as a weight 25 acting through a cord 26 over a pulley 27 serves to urge the member 23 to swing toward the pouncing pads. Hence the hat block, carried at the upper end of the member 23 is urged inwardly toward the pouncing tools, this inward movement being limited by the band portion of the hat coming against the outer end of the upper pad 10. As the oval hat rotates, the distance between its axis of rotation and the pouncing tools is continually changing and hence the hat swings bodily about the pivot 24 toward and away from the tools.

In the position of the parts shown in Figure 1, the hat is turned so that its major axis is at right angles to the pouncing tools and hence the supporting shaft 23 is swung outwardly about its pivot 24. It will be seen that the shaft 23 and hence the hat are substantially tilted. As the side portions of the hat approach the pouncing tools, the hat will move inwardly toward the tools and the shaft 23 will swing toward the vertical. Preferably, the pivot 24 is so positioned that, when the side portions of the hat brim are being operated upon, the shaft 23 is still somewhat inclined. This permits the lower pouncing pad 11 to operate at all times all the way up to the inner edge of the brim, as will be seen by a consideration of Figure 1.

As will be seen from Figure 1, the hat 14 shown herein is not flat at the inner edge of the brim, or at what is known as the "band" of the hat. The hat is "dished" at the band from end to end, the band being substantially higher at the sides of the hat than it is at the ends thereof. The bottom surface of the block 16 is correspondingly "dished", this shaping of the block being ordinarily known as the "scope" of the block. Because of this "dish" or "scope" of the hat, if the hat is rotated without its vertical position being changed relative to the pouncing pads, the portion of the band passing by the pads rises and falls as the hat rotates. This results in a movement of the band or the inner edge portion of the brim, at certain portions thereof, either above or below the proper position for engagement with the pouncing pads. In order to cause all portions of the band to move through the proper point adjacent the pouncing tools, when a "dished" hat is being operated upon provision is made for causing a bodily up and down movement of the hat so that the hat is raised when the end portions thereof approach the tools and lowered when the side portions approach the tools.

Adjacent to the lower pouncing pad 11 and preferably directly in front thereof, there is provided a stationary member 28 which may be carried upon a suitable bracket 29 secured to the frame of the machine. As the hat block is rotated, the bottom surface 16^a of the hat block moves across the upper surface of this member 28 which is preferably small and narrow so that it contacts only a small portion of the hat block at one time.

As the hat block moves across the surface of the member 28, all portions of the brim are caused to be brought into proper engagement with the pouncing tools, the effect being to cause all portions of the band of the hat to move substantially through a fixed point directly in front of the brim receiving space between the two pouncing pads

regardless of the "scope" of the hat block and hat. This guiding of the path of movement of the hat block past the pouncing tools necessitates a rising and falling of the hat block. The hat block is permitted a bodily up and down movement preferably by the supporting member 20 being slideable in the member 23. Thus, as the hat block rotates, it partakes of an up and down movement substantially lengthwise of its axis of rotation in addition to a movement of its axis of rotation toward and away from the pouncing pads. 70

It is highly desirable that the up and down movement of the hat block take place with the greatest possible ease and with a minimum of friction. It is unsafe to use lubricant within the bushing 19 of the hat block because of the danger of oil or grease coming into contact with the hats. In order to enable the lifting of the hat to take place with the least resistance, means is provided herein for substantially counter-balancing the weight of the hat block and the parts which are lifted therewith. Preferably, a spring 30 is provided between the supporting member 20 and the shaft 23, which spring urges the member 20 upwardly with a force very slightly less than the combined weight of the part 20 and the hat block and hat carried thereby. As shown in the drawing, the upper portion of the shaft 23 is made hollow and the member 20 slides in this hollow portion, the spring 30 being positioned in the bottom thereof. A stop taking the form of a suitable screw 31 limits the upward movement of the member 20 under the urge of the spring after the hat block has been removed. 85

Lubricant may be applied to the sliding surfaces of the members 20 and 23 without danger of soiling the hats, and so as to permit free up and down movement of the member 20. No lubricant is required within the bushing 19. Because of the counter-balancing effect of the spring 30, the hat block rests only very lightly upon the surface of the member 28. This mounting, in addition to the advantages already pointed out, thus causes substantially a floating of the hat brim between the pouncing pads so that there is no great difference between the pressure of the hat brim against the lower pad and the pressure of the hat brim against the upper pad. This makes possible a more uniform pouncing of the brim. 100

In pouncing hat brims, it is frequently found that the brim requires less pouncing at its inner portion adjacent the band of the hat than it does at the outer portions thereof. In order to effect pouncing of the hat brim to a greater extent at its outer portion than at its inner portion, there is provided herein a removable stop for limiting the movement of the hat into the pouncing pads under the 110

urge of the counter weight 25. This device preferably takes the form of an arm 32 which is pivoted at 33 upon an upright 34. The upright 34 may be mounted conveniently upon a bracket 35 which extends outwardly from the bracket 29. The upright 34 and the arm 32 carried thereby are thus stationary not reciprocating with the pouncing pads. In Figure 1 the arm 32 is shown 10 swung back into inoperative position, in which position it may be held conveniently by a projection 36 of the arm 32. To place the arm 32 in operative position, it is simply swung forwardly about its pivot 33 to a 15 horizontal position wherein it may be supported by a projection 37.

Referring to Figure 2, the arm 32 is shown swung into operative position and holding the hat 14 away from the pouncing pads so that the brim does not enter completely within the pads. As shown in Figure 2, the arm 32 is provided with an angular projection 32^a which has a curved face 32^b against which the hat bears. This curved surface 32^b engages the crown of the hat adjacent to the band portion thereof. In the operation of the machine, the hat may be given a few turns with the stop 32 in operative position to pounce the brim only at the outer portions thereof, and thereupon the arm 32 may be moved to inoperative position for pouncing of the brim throughout its entire width.

As many possible embodiments may be made of the above invention and as many changes might be made in the embodiment above set forth, it is to be understood that the matter hereinbefore set forth or shown in the accompanying drawing, is to be interpreted as illustrative and not in a limiting sense.

I claim as my invention:

1. In apparatus of the class described, in combination, a support for a hat, a tool adapted to operate upon the brim of a hat mounted on said support, means adapted to give said hat an up and down movement as it is operated upon, and means adapted substantially to counterbalance the force of gravity upon said hat.

2. In apparatus of the class described, in combination, means adapted to rotatably support a hat block, a tool adapted to operate upon a hat carried by said hat block, means adapted to rotate said hat block with said hat thereon, means adapted to give said hat block an up and down movement as it is rotated, and means adapted substantially to counterbalance the weight of said hat block and the parts which move up and down therewith.

3. In apparatus of the class described, in combination, means adapted to support a hat block for rotation about a substantially up-

hat carried by said hat block, means adapted to rotate said hat block with said hat thereon about said substantially upright axis, means adapted to lift and lower said hat block substantially longitudinally of its axis of rotation, and means for substantially counterbalancing the weight of said hat block and the parts lifted and lowered therewith.

4. In apparatus of the class described, in combination, means adapted to support a 70 hat block in substantially upright position and having a spindle adapted to enter a recess in the bottom of said hat block, a tool adapted to operate upon a hat carried by said hat block, means adapted to rotate said 75 hat block about the axis of said spindle, means adapted to raise and lower said supporting means during rotation of said hat, and means adapted substantially to counterbalance the weight of said supporting means 80 and said hat block and said hat carried thereby.

5. In apparatus of the class described, in combination, means adapted to support a hat block in substantially upright position and 90 having a spindle adapted to enter a recess in the bottom of said hat block, a tool adapted to operate upon a hat carried by said hat block, means adapted to rotate said 95 hat block about the axis of said spindle, a member carrying said hat block supporting member and in which said supporting member is slidable in a direction substantially lengthwise of the axis of rotation of said hat, and a spring urging said supporting member to move in said last member in a direction to lift said hat block.

6. In apparatus of the class described, in combination, means adapted to support a hat block in substantially upright position for rotation and up and down movement substantially lengthwise of its axis of rotation, a tool adapted to operate upon a hat carried by said hat block, means adapted to rotate said hat block as said hat thereon is operated upon by said tool, means adapted to guide said rotating hat block to give it an up and down movement as it is rotated, and means adapted substantially to counterbalance the weight of said hat block.

7. In apparatus of the class described, in combination, means adapted to support a hat block in substantially upright position for rotation and up and down movement substantially lengthwise of its axis of rotation, a tool adapted to operate upon a hat carried by said hat block, means adapted to rotate said hat block as said hat thereon is operated upon by said tool, a member adjacent said tool across which the bottom surface of said hat block moves during rotation thereof, and means adapted substantially to counterbalance the weight of said hat block.

8. In apparatus of the class described, in

- combination, a tool adapted to operate upon a hat, a support adjacent said tool movable toward and away from said tool, means urging said support toward said tool, means 5 upon said support adapted to support a hat block in substantially upright position for rotation and up and down movement substantially lengthwise of its axis of rotation, means adapted to rotate said hat block, 10 means adapted to give said rotating hat block an up and down movement, and means adapted substantially to counterbalance the weight of said hat block upon said supporting means.
- 15 9. In apparatus of the class described, in combination, a tool adapted to operate upon a hat, a substantially upright member mounted to swing toward and away from said tool, a support adjacent the upper end 20 of said member adapted to support a hat block for rotation adjacent said tool, said support being slidable upwardly and downwardly in said member, means for rotating said hat block, means adapted during said 25 rotation to give said support and said hat block therewith an up and down movement, and spring means interposed between said member and said support urging upwardly said support and said hat block thereon.
- 30 10. In apparatus of the class described, in combination, a tool adapted to operate upon a hat, a substantially upright member mounted to swing toward and away from said tool, a support adjacent the upper end 35 of said member adapted to support a hat block for rotation adjacent said tool, said support being slidable upwardly and downwardly in said member, means for rotating said hat block, means adapted to guide said 40 rotating hat block to give it an up and down movement, and spring means urging said hat block support upwardly in said member.
11. In apparatus of the class described, in combination, a tool adapted to operate upon 45 a hat, a substantially upright member mounted to swing toward and away from said tool, a support adjacent the upper end of said member adapted to support a hat block for rotation adjacent said tool, said 50 support being slidable upwardly and downwardly in said member, means for rotating said hat block, means adjacent said tool across which the bottom surface of said hat block moves during rotation, and spring means urging said hat block support upwardly in said member. 55
12. In apparatus of the class described, in combination, a tool adapted to operate upon a hat, a substantially upright member mounted to swing toward and away from 60 said tool, a support adjacent the upper end of said member adapted to support a hat block for rotation adjacent said tool, said support being slidable upwardly and downwardly in said member, means for rotating said hat block, means adjacent said tool across which the bottom surface of said hat block moves during rotation, spring means urging said hat block support upwardly in said member, and means for limiting the 65 upward movement of said hat block support under the urge of said spring means. 70
13. In apparatus of the class described, in combination, means adapted rotatably to support a hat, a reciprocating tool adapted to operate upon the brim of said hat, means adapted to rotate said hat, means adapted to urge said hat toward said tool to urge the brim into engagement with said tool, and a member with respect to which said tool reciprocates and having an elongated curved 75 surface adapted to engage the crown of said hat to limit the movement of said hat toward said tool, said member being movable into and out of operative position. 80
14. In apparatus of the class described, in combination, means adapted rotatably to support a hat, a pair of reciprocating pounding pads adapted to receive the brim of said hat therebetween and operate thereon, means adapted to rotate said hat to feed said brim between said pads, means for urging said hat toward said pads, and a device mounted independently of said reciprocating pads adapted to engage the crown of 85 said hat adjacent the band and limit the movement of said hat toward said pads so as to enable said pads to operate upon the outer portions only of said brim. 90
- In testimony whereof, I have signed my name to this specification this 1st day of June, 1926. 100

RALPH K. REYNOLDS.
